(57) **CLAIM**

The ornamental design for an LED portable generator panel, as shown and described.

DESCRIPTION

FIG. 1 is a front perspective view of an LED portable generator panel according to the present invention;

FIG. 2 is a back perspective view of the LED portable generator panel of FIG. 1;

FIG. 3 is a front view of the LED portable generator panel of FIG. 1;

FIG. 4 is a back view of the LED portable generator panel of FIG. 1;

FIG. 5 is a first side view of the LED portable generator panel of FIG. 1;

FIG. 6 is a second side view of the LED portable generator panel of FIG. 1;

FIG. 7 is a top view of the LED portable generator panel of FIG. 1;

FIG. 8 is a bottom view of the LED portable generator panel of FIG. 1;

FIG. 9 is another front perspective view of the LED portable generator panel of FIG. 1; and,

FIG. 10 is another front perspective view of the LED portable generator panel of FIG. 1 showing controls and outlets.

The features shown in broken lines in the drawing depict environmental subject matter only and form no part of the claimed design.
